UNITED STATES PATENT OFFICE.

ARNE CHRISTOPHERSON, OF CANTON, SOUTH DAKOTA.

DISK-SHARPENER.

SPECIFICATION forming part of Letters Patent No. 603,172, dated April 26, 1898.

Application filed June 18, 1895. Serial No. 553,249. (No model.)

To all whom it may concern:

Be it known that I, ARNE CHRISTOPHERSON, a citizen of the United States, residing at Canton, in the county of Lincoln and State of 5 South Dakota, have invented certain new and useful Improvements in Disk - Sharpeners; and I do hereby declare the following to be a full, clear, and exact description of the invention, such as will enable others skilled in 10 the art to which it appertains to make and use the same.

The object of my invention is to provide a disk-sharpener for use in sharpening harrow-wheels and other wheels of like character 15 which will be simple in construction, which will automatically adjust itself to sharpening irregular or wobbling disks as well as regular disks, and which will be capable of adjustment to sharpen a disk at any angle desired.

20 In accomplishing the object of my invention I mount the disk to be sharpened upon a shaft which is rotated by suitable power mechanism and provide a second or supplemental shaft parallel to the first or main shaft, but at a distance therefrom greater than the radius of the disk to be sharpened, upon which is adjustably mounted a support 25 for the sharpening-knife. The support for the sharpening-knife is made in two parts, 30 which are hinged or jointed together, so as to allow the upper part to move independently of the lower part and thus to follow any irregularity in the surface of the disk being sharpened. The sharpening-knife itself is adjust- 35 ably secured in the end of the upper section of the knife-support and is held pressed against the edge of the disk to be sharpened by a spring-guide. This guide consists of an angled arm on which are mounted two trolley-wheels, which roll upon the outer surface 40 of the disk being sharpened. The angled arm is pivotally connected to an arm rigidly held at right angles to the sharpening-knife. The pressure with which the trolley-wheels 45 bear against the disk-surface is regulated by the adjustment of a spring connecting the two parts, so that the sharpening-knife may be held with any desired degree of firmness against the surface being sharpened. The 50 sharpening-knife itself is so made that it can be removed and replaced at will, so that by using different forms of sharpening-knives

any desired angle can be given to the edge of the disk being sharpened.

My invention is fully illustrated in the drawings which accompany and form a part of this specification, in which the same reference letters and numerals refer to the same or corresponding parts, and in which—

Figure 1 is a perspective view of my disk-sharpener, showing a series of harrow-wheels in position on the main shaft to be sharpened. Fig. 2 is a detail view of that one of the harrow-wheels which is about to be sharpened, showing the sharpening-knife and knife-support. 65 Figs. 3 and 4 are details of the knife-support.

Referring to the drawings, A represents the frame of the sharpener. On this frame are mounted supports B for the main shaft C, the 70 bearings b being adjustable, so as to permit the shaft to be readily removed from the frame for the purpose of putting on the same the disks which are to be sharpened and removing disks already sharpened. The shaft 75 C is rotated through the action of the meshing gears 1 and 2, gear 2 being keyed to the power-shaft 3, to which power is conveyed by the belt-wheel 4.

On the main shaft C are mounted, as has 80 just been stated, the disks to be sharpened. The disks D shown in the drawings are harrow-wheels, and, as shown, a number of the wheels or disks can be placed on the shaft at the same time, so as to permit them to be 85 sharpened successively without necessitating readjustment of the machine after the sharpening of each disk. The disks are held a suitable distance apart from each other on the shaft by spaces c, which may be of any 90 desired shape. The harrow wheels or disks are secured firmly to the shaft, so that they rotate with the same.

The knife-sharpener E is adjustably mounted upon the supplemental shaft F, which is 95 parallel to the main shaft C, but at a distance therefrom greater than the radius of the disk to be sharpened. The supplemental shaft F is itself mounted upon the stud-shafts f, which pass through the ends of the 100 same, being held on the stud-shafts by the set-screw f'. In this manner adjustment of the distance between the centers of the main and supplemental shafts is possible and pro-

vision is made for the sharpening of disks greatly differing in diameter.

The supplemental shaft F is, in effect, a slide-bed, upon which the knife-support can 5 be adjusted. With it there is possible an adjustment of the knife-support axially of the shaft as well as lengthwise of the shaft. This is a feature which I believe to be new in the art and which I have found to be of 10 great utility.

The knife-support E is made in two portions or sections, the lower part E', which is held in any given position on the supplemental shaft by the set-screw e', and the upper 15 part E², which bears the sharpening-knife and the mechanism employed to hold the sharpening-knife against the surface of the disks being sharpened. The connection between the two parts of the knife-support E 20 is pivotal in its character, so that the upper part of the support can move relative to the lower part and can thus follow any irregularities of the surface of the disk being treated. The sharpening-knife G passes through 25 an opening made therefor in the knife-support and is held in position by a set-screw g. Any character of cutting-knife may be employed, and by changing the knives edges of different angles may be given to the disks 30 being sharpened. The sharpening-knife is held against the surface of the disk being sharpened by the spring-support H, consisting of the bracket H', extending outward from the knife-support at right angles there- 35 to, and the angled arm H², pivotally secured to said bracket and bearing on the ends of its angled portion trolley or friction wheels h². The length of the angled arm H² is such that the trolley-wheels h² always bear against 40 the surface of the disk at some little distance from the periphery thereof, insuring the sharpening-knife being held firmly against the surface of said disk. The pressure with 45 which the trolley-wheels bear against the disk-surface can be adjusted by adjusting the screw I, which connects the bracket H' with the angled arm H², the spring J acting to force the angled arm H² and bracket H' together. 50 The construction which I have thus de- 55 scribed enables me to sharpen disks of any diameter and however irregular in outline quickly and easily and to give their edges any desired angle. A number of disks can be on the sharpening-shaft at the same time, so that the adjustment from one disk to another is only the matter of a moment.

Having thus fully described my invention, what I claim as new, and desire to secure by 60 Letters Patent, is—

1. In a disk-sharpener, the combination

with a frame, a shaft adapted to have mounted thereon the disks to be sharpened, bearings therefor, and means for rotating said shaft, of a supplemental shaft parallel to said main shaft, and distant therefrom more than the radius of the disk to be sharpened, a knife-support adjustably mounted thereon, and solely carried thereby and a sharpening-knife, substantially as described. 70

2. In a disk-sharpener, the combination with a frame, a shaft adapted to have mounted thereon the disks to be sharpened, bearings therefor, and means for rotating said shaft, of a supplemental shaft parallel to said main shaft and distant therefrom more than the radius of the disk to be sharpened, a knife-support consisting of two sections, one section being adjustably mounted on said supplemental shaft, and solely carried thereby and 75 the other section, bearing the sharpening-knife, being pivotally connected to the outer end of the first section, a knife, and means for holding the same against the edge of the disk to be sharpened, substantially as de- 80 scribed. 85

3. In a disk-sharpener, the combination with a frame, a main shaft adapted to have mounted thereon the disks to be sharpened, bearings therefor, and means for rotating said shaft, of a supplemental shaft parallel to said main shaft and distant therefrom more than the radius of the disk to be sharpened, said supplemental shaft being adjustable as to its 90 distance from the main shaft, a knife-support 95 consisting of two sections, one section being adjustably mounted on said supplemental shaft, and solely carried thereby and the second section bearing the sharpening-knife, and being pivotally connected to the outer end of 100 the first, a knife, and means for holding the same against the edge of the disk to be sharpened, substantially as described. 105

4. In a disk-sharpener, the combination with a frame, a main shaft adapted to have 105 mounted thereon the disks to be sharpened, bearings therefor, and means for rotating said shaft, of a supplemental shaft parallel to said main shaft but distant therefrom more than the radius of the disks to be sharpened, a knife- 110 support adjustably mounted thereon, said knife-support being made in two parts hinged together, a knife, and a bracket H', angled arm H² bearing trolley-wheels h², screw I, and 115 spring J for holding said knife against the disk to be sharpened, substantially as described.

ARNE CHRISTOPHERSON.
